[57] CLAIM

The ornamental design for a confection holder, as shown and described.

DESCRIPTION

FIG. 1 is a perspective view of a confection holder, the portions shown in dotted lines being included for environmental purposes and form no part of the invention.

FIG. 2 is a top plan view of the confection holder.

FIG. 3 is a front elevational view of the holder.

FIG. 4 is a side elevational view of the holder.

FIG. 5 is a rear elevational view of the holder; and,

FIG. 6 is a bottom plan view of the holder.
